INVESTING MACHINE

Ernest L. Hildreth, Los Angeles, Calif.

Application November 25, 1949, Serial No. 129,413

3 Claims. (Cl. 22—65.1)

1

The present invention relates to an investing machine of the type adapted for investing wax patterns for dental and small industrial castings.

An object of the invention is the provision of an investing machine of simple construction, easy to operate, and capable of producing superior results.

A smooth and accurate plaster matrix of a wax pattern is assured by the present invention.

A further object is the provision of an investing machine adapted to centrifuge the investment material about the pattern and in such a manner that the investment material is densely packed, and substantially free from gases and excess water.

A further object is the provision of an investing machine of attractive appearance, wherein certain of the operations to be performed by the machine may be observed, and which machine is generally superior to devices now known to the inventor.

With the above-mentioned objects, including simplicity of structure and inexpensiveness in cost of manufacture, the invention consists in the novel and useful provision, formation, construction, association and relative arrangement of parts, members and features, all as shown in certain embodiments in the accompanying drawing, described generally and more particularly pointed out in the claims.

In the drawing:

Figure 1 is a top plan view of one form of the invention;

Figure 2 is a top plan view of a modified form of the invention;

Figure 3 is a vertical sectional view on the line 3—3 of Figure 1;

Figure 4 is a vertical sectional view on the line 4—4 of Figure 2;

Figure 5 is a transverse sectional view on an enlarged scale on the line 5—5 of Figure 3; and

Figure 6 is a vertical sectional view on an enlarged scale on the line 6—6 of Figure 4.

Referring now with particularity to the drawing, the investing machine includes a casing having an annular side wall 1, a base 2, and a rubber disc 3 positioned between the wall 1 and base. Within the confines of the casing is an enlarged annular block 4 supported on the disc 3. Block 4 surrounds a motor 5 secured to vertical posts 6, the posts being mounted on the member 3. The block 4 is recessed at 7 and the base 2 is formed with a bore permitting passage of an electrical cable 8 into the casing for connection with the motor, as shown. The shaft of the motor stands

2

vertically and substantially in the axis of the casing, the said shaft supporting for rotation a spider 9. The spider 9 in the present instance is secured to the motor shaft in any approved manner, such as by the nut 10 and said spider is provided with four equi-distantly spaced-apart arcuate recesses 11, 12, 13 and 14, the construction providing four spaced pairs of arms as indicated at 15 and 16 for one pair. Rings 17 are mounted 10 between each pair of arms (see Figure 5). The rings are diametrically held by screws designated generally by 18 which are transversely passed through the arms for engagement with the ring, there being a spacer member 19 carried on each 15 screw and interposed between the arms and the ring in each instance.

The form of the invention shown in Figures 2 and 4 does not differ essentially from the form shown in Figures 1 and 3, save and except that 20 two spaced pairs of arms are provided, as indicated at 20 and 21, and mounted between said arms are rings 22. The rings 22 are larger in diameter than the rings 17 and for reasons which will hereinafter appear.

25 In the practice of that form of the invention shown in Figures 1 and 3, I utilize four cups or buckets 23 of the form shown in Figure 5.

Each bucket or cup is provided with an out-turned lip or flange 24, which lip is adapted to 30 engage the upper surface of the ring 17 for supporting the cup. The cup or bucket is of a size which permits reception therein of a sprue former 25, an investment ring 26 carried by the sprue former, and a hopper 27, supported on the upper 35 end of the investment ring. The sprue former has the usual convex crucible forming portion 28, provided with an axial bore 29 adapted to receive sprue pin 30. The sprue pin carries a pattern 31 of some form.

40 The hopper 27 has a base 32, the outer surface of which is recessed to provide an annular flange 33, which flange surrounds the upper end of the investment ring. The side wall of the hopper is conical in form and provided with an external 45 annular bead 34, which bead is adapted to engage the inner surface of the bucket or cup for stabilizing the hopper. The inner surface of the side wall is inclined or conical in form for the purpose of directing any material therein toward a central perforation 35 in the base. The side wall and base is bored at 36 to provide a vent for the investment ring. The hopper adjacent its outermost end is provided with an annular 50 shoulder 37 and a transparent cap 38 provided

with a central perforation 39 is adapted to overlie the hopper and be positioned on said shoulder.

In the form of the invention shown in Figures 2, 4 and 6, the bucket or cup 40 has less depth and greater diameter than the bucket or cup 23. The investment ring 41 is internally shouldered at each end, as shown at 42 and 43, the lower shoulder engaging the shoulder 44 of a base member 45. A hopper 46 rests upon the shoulder 42. This hopper is provided with a central vent tube 47 which extends through the base 48 of the hopper. The base 48 is provided with a series of spaced radially arranged transverse perforations 49. This form of the invention is particularly adaptable for dentures.

The operation, uses and advantages of the invention just described is as follows:

Taking that form of the invention shown in Figures 1, 3, and 5, it is essential that the buckets, investment ring, sprue former, hopper and cap should all be of the same weight. In fact, the weight of investment material used in the respective hoppers should be the same. To this end, a scale is employed for weighing the said members. After the wax pattern 31 has been formed, and impaled on sprue pin 30, the sprue pin is placed in the bore 29 of the sprue former and sprue former is placed in a bucket 23. The investment ring with its asbestos insert is then placed in position surrounding the pattern. Following this, the hopper is placed over the investment ring and the investment material in a weighed and measured quantity is poured into the hopper. The transparent cap is then positioned over the hopper, and the assembly has the appearance shown in Figure 5. As shown, four patterns and buckets may be utilized, or if only one pattern is used, then two assemblies are placed diametrically of the spider, with both assemblies holding a like weight of investment material.

A transparent cover 50 is provided for the casting, the cover being in gasket sealed relationship therewith, as shown at 51. In the present instance, the base 2 is bored to accommodate a tube 52, which communicates with the bore of the annular block 4. This tube leads to a vacuum pump, not shown. The first procedure after investment material is placed in a hopper or two hoppers in diametric position, is to operate a valve leading to the vacuum pump, to the end that the entire casing is placed under vacuum. This condition may be determined by a gauge in the usual manner. While maintaining a vacuum within the casing, the motor 5 is energized which will cause the buckets to revolve on their pivots and assume an axially horizontal position. When this occurs, the investment material will be directed by centrifugal force through the perforations 35 of each hopper and into the investment rings to surround the wax pattern or patterns 31. Centrifugal force in addition to directing the investment material through the perforations 35 also acts to extract under the vacuum conditions maintained, excess water and gas in the investment material, with the result that the investment material is formed into a hard compact mold about the wax pattern.

After the investment material has been deposited from the hopper into the investment ring, the material is allowed to set for a given period of time, as determined by the characteristics of the particular investment material selected. Thereafter, the assembly may be removed from the buckets, the sprue pin removed, and the wax pattern burned from the matrix in the usual

manner. It will be found that the use of centrifugal force and a maintained vacuum condition within the hopper and investment ring produces a very hard smooth matrix and one that gives perfect results so far as the resultant casting is concerned. It is obvious that the vent 36 allows gases to escape from the investment ring to the perforation 39 in the cap.

The entire assembly is held against movement within the bucket when the parts are in the position shown in Figure 5 with the annular bead 34 engaging the inner surface of the bucket. Vibration is no problem in the practice of the present invention, although it is a problem in the average centrifuge.

In the operation of that form of the invention shown in Figures 2, 4 and 6, the wax pattern 53 is shown in a support of investment material 54. This investment material has a wire 55 embedded therein to give stability and aid in maintaining form. As before, the two assemblies, such as shown in Figure 6, are preferably weighed, so that there will not be vibration when the spider is rotated by the motor. The investment material is placed within the hopper 46 and under centrifugal force, the investment material passes through the perforations 49 to surround the investment material 54 and to enclose the wax pattern 53. As before, gases, excess water and the like may pass through the vent tube 47 under vacuum conditions. Upon completion of the passage of the investment material from the hopper into the investment ring 41, the investment material is allowed to harden, whereupon the wax pattern may be melted therefrom, followed by the usual metal casting operation.

The present invention may be utilized for purposes other than the investing of wax patterns, as it may be used for making plaster casts or models which are centrifuged from the hoppers into the impressions.

I claim:

1. An investment machine, including: a casing, a motor and its shaft centrally positioned within said casing; a spider carried by said shaft; said spider being provided with equi-distantly spaced-apart arcuate recesses; a ring positioned within each recess; means for pivoting each ring to said spider; a bucket pendant from each ring; an investment ring and base member therefor within the bucket; a hopper supported on the investment ring; said hopper being formed with a side wall and a base, the base of which is provided with a perforation and a vent opening extending through the side wall from the base of the hopper to adjacent the top thereof, both the vent opening and said perforation communicating with the interior of the investment ring, and means for placing the interior of said casing under vacuum conditions.

2. An investment machine, including: a bucket, a sprue former carried by said bucket, an investment ring for said sprue former, a hopper carried by the investment ring, and a cap for the hopper, said hopper having a conical side wall, and a base, the said base being formed with an opening leading to the interior of the investment ring, said side wall of the hopper being provided with a bore extending from the top of said wall through the base to provide a vent, the said vent communicating with the interior of the investment ring.

3. An investment machine, including: a casing, a motor and its shaft centrally positioned within said casing; a spider carried by said shaft; said

spider being provided with equidistantly spaced-apart arcuate recesses; a ring positioned within each recess; means for pivoting each ring to said spider; a bucket pendant from each ring; an investment ring and base member therefor within the bucket; a hopper supported on the investment ring; said hopper being formed with a side wall and a base; the base of which is provided with a perforation, said side wall of the hopper being provided with a bore extending from the top of said wall through the base to provide a vent, both the vent and said perforation communicating with the interior of the investment ring.

10 ERNEST L. HILDRETH.
